UNITED STATES PATENT OFFICE.

P. W. GATES, OF CHICAGO, ILLINOIS.

IMPROVEMENT IN APPARATUS FOR EVAPORATING SACCHARINE LIQUIDS.

Specification forming part of Letters Patent No. 36,949, dated November 18, 1862.

To all whom it may concern:

Be it known that I, P. W. GATES, of Chicago, in the county of Cook and State of Illinois, have invented a new and useful Improvement in Steam-Coil Evaporators for Sugar and Sirup Juices; and I do hereby declare that the following is a full, clear, and exact description of the same, reference being had to the accompanying drawings, forming part of this specification, in which—

Figure 1 is a plan of an evaporator with my invention applied to it. Fig. 2 is a vertical longitudinal section of the same. Fig. 3 is a vertical transverse section of the same. Fig. 4 is a plan of the invention applied to a slightly-modified form of evaporator. Fig. 5 shows the damper part of the invention applied in connection with a pan which cooks exclusively by fire.

Similar letters of reference in the several figures indicate corresponding parts.

The nature of my invention consists in the combination of the fire-arch having a divided fire-flue, damper, and lateral hot-air flue with an evaporator-pan having a defecating-apartment and a finishing-apartment, as hereinafter described.

It consists, secondly, in the combination, with the fire-arch having a divided fire-flue and damper, of steam-coils which operate in concert with the fire-arch in evaporating the juices in the manner hereinafter described.

A, Figs. 1, 2, 3, and 5, is a fire-arch with a lateral extension, A', near its front end. This extension is built up so as to form a hot-air flue, which communicates with the fire-chamber of the arch.

B' are preparatory heaters mounted upon an elevated part of the arch, said part of the arch being forward of the extension.

C is an evaporating-pan with lateral defecating-apartment C'. The sides C¹ C² of this pan, except where the defecator is formed, are set inclined, as shown in Fig. 3. The ends of the pan and the inclosing sides of the defecator are vertical. The bottom of the defecator is a lateral continuation of the bottom of the pan, and the juice flows freely from the same upon the bottom of the pan. The pan with defecator is set upon the rear lower portion of the arch and the extension thereof, so as to incline downward to a slight

extent as it runs backward. The defecator C' rests upon the part A' of the arch, and below it an air-chamber communicating with the fire-flue of the part A of the arch exists. By means of this arrangement of air-chamber the heat from the fire circulates moderately under the defecator, and heats the same sufficiently to bring the flowing juice up to nearly the boiling-point. At the extreme rear end of the pan to one side a vertical discharge-gate, a, which opens and closes a let-off passage, b, is constructed as represented. The preparatory heaters, as described, are well adapted for use in connection with the pan; but they may be dispensed with, as circumstances may suggest. The pan near its rear end—say about one foot and six inches from said end—has a tight transverse partition, **, fitted to it, as shown in Fig. 5 in black lines, and in Figs. 1 and 2 in red lines, and to thus employ this partition the flue D of the arch A is divided by a wall, d, into two flues, e f, which unite into one just before they arrive at the chimney E of the arch. They also of course unite into one flue forward of the wall d. In connection with the flues e f a damper, F, is employed. This damper is hinged to the front end of the wall, and answers for both flues e and f. The black lines show the damper closing the flue f, and the red lines show it closing the flue e. The flues e and f occupy about the last fourth of the arch-flue.

I sometimes arrange on the bottom of the pan steam-coils G G'. One or more of the bends of these coils may extend from end to end of the pan, as indicated at h h, while the remaining or continuing bends h' h'' only extend forward a distance equal, or thereabout, to the length of the flues e f, as shown. This, however, must be according to circumstances. The first bends, h h, are on the central part of the bottom of the pan, and their receiving ends unite with a common supply-pipe, h¹, of a steam-generator. The last bends, h'' h'', run along the margins of the pan and unite with a common exhaust-pipe, h³. The receiving and exhausting ends of the pipes are to be provided with proper regulating-cocks. Instead of having some of the coils or bends short and others long, they may all be of the same length and extend from end to end of the pan.

In Fig. 4 I have shown the steam-coils and

the pan as used when the preparatory cleansers and heaters are not employed. In this construction the elevated part of the arch which supported the preparatory cleansers and heaters is not erected. This plan I prefer on account of its simplicity.

I will here state that one of the steam-coils, G, with bends of unequal or uniform length, may be used alone, but in that case one side of the pan (that side where there is no defecator) should be vertical and the other side inclined, except at that point where the defecator is located. The receiving-bends in such use would run alongside the vertical side of the pan instead of at the center of the bottom of the pan.

The operation of the invention, when fire alone is used for evaporating the juice, is as follows: The juice being introduced into the defecator C' from either the preparatory heaters and cleansers or directly from a reservoir, s, the moderately-heated condition of the defecator causes the juice to be raised to nearly the boiling-point, and the green scum and souring matter thereof to be thrown upon the surface of the juice, and as a strong ebullition sets in from the boiling fluid or juice in the pan C, such deleterious scum is prevented from flowing into the pan. Therefore the operator has an opportunity to skim it off. The juice, as it flows over the surface of the bottom of the pan, is caused by the heat of the arch-fire to deposit its scum upon the inclined sides of the pan. As fast as the juice is thus evaporated and purified, it is dipped over into the chamber formed by the partition **, and is finished in this chamber in "batches" of three to five gallons, and the double flue e f and damper serve to convey the fire away from the bottom of this chamber, and thus keep the finished sirup and pan from burning while the sirup is being drawn off and another batch is being dipped over the partition to be finished in like manner, as just described. The heat of the fire is of course allowed to act upon the batch of sirup after the same is dipped over into the chamber.

The operation of the invention when fire and steam combined are used to evaporate the juice is as follows: The juice in passing through the defecator and over the steam-coils is deprived of its impurities in the same manner as in the fire-pan, excepting that the deposit of the scum by the intensely-heated receiving steam-bends of the coils is more rapid, owing to the boiling at the center of the pan being more violent from the effect of the steam

and fire combined; and while this is the case there is, with proper care, no danger of scorching the juice, as the fire-heat is not increased, but on the contrary may be decreased when the steam is used. As the juice flows along the coils and bottom of the pan, it may be arrested by a tight transverse partition, **, (shown in red lines in Figs. 1 and 2,) and dipped over the same into the finishing-chamber, and there finished in batches of from three to five gallons, and while being drawn off the course of the fire and the circulation of the steam may be cut off from it, or the partition may be fitted loose, so that the juice flows under it and directly off through the gate, or the partition may be removed altogether, as represented in Fig. 4.

There is great economy in using steam-coils, as the steam-generator which operates the cane-mill of an establishment may be employed to aid in evaporating the juice at a slight additional cost.

There is also advantage in finishing the juice in batches, as the operation of evaporating on the greater surface of the pan may be carried on rapidly and the finishing operation performed leisurely without loss of time. The finishing operation is the bringing of the purified juice to the proper consistency for making sirup or sugar, and to do this too speedily renders scorching liable, and to lose time in accomplishing the same in many instances is impracticable; hence the utility in finishing in large batches while the evaporating on the main surface of the pan is proceeding.

It also is very essential to first defecate the juice, and finally it is important to have the fire under control at the end of the pan, both while the juice is finished in batches or while continuously flowing.

What I claim as my invention, and desire to secure by Letters Patent, is—

1. The combination of the fire-arch, damper, evaporating-pan, and defecating and finishing chambers, arranged in the manner and for the purposes herein set forth.

2. The combination, with the fire-arch and damper, of steam-coils G G' and evaporating-pan C C', substantially as and for the purposes herein described.

3. The construction of the steam-coils with long and short bends, substantially as and for the purpose described.

P. W. GATES.
